UNITED STATES PATENT OFFICE.

DAVID T. DAY, OF WASHINGTON, DISTRICT OF COLUMBIA

APPARATUS FOR THE COMBINED SOLVENT AND DESTRUCTIVE DISTILLATION TREATMENT OF SHALE.

Application filed December 7, 1920. Serial No. 428,913.

To all whom it may concern:

Be it known that I, DAVID T. DAY, a citizen of the United States, residing at Washington, in the District of Columbia, have invented certain new and useful Improvements in Apparatus for the Combined Solvent and Destructive Distillation Treatment of Shale, of which the following is a specification.

This invention relates to an apparatus for effecting the extraction of oil from oil bearing shale and provides for extraction with a liquid bath of solvent combined with destructive distillation.

The invention provides specifically the apparatus in which a bath or pool of liquid solvent is provided and into which fresh shale is passed, the partial extraction of the oil in the shale by the solvent, the removal of the shale from the bath of oil, and the subsequent distillation of the shale so removed to effect cracking of the oil therein and the production of oil for the maintenance of the oil bath.

The apparatus has made it possible to obtain a larger total yield of oil than is ordinarily possible by either the usual solvent extraction or by destructive distillation. Solvent extraction may remove three times as much oil from shale as is possible by destructive distillation. The present invention combines the solvent features with distillation in a way that uses the products formed during distillation to serve as material for the solvent bath.

Claims directed to the particular process described in this specification are presented in my copending divisional application Serial No. 585,174, filed August 30, 1922.

The advantageous results made possible by the invention are due also in part to the heat exchange wherein the heat of condensation of the vapors within the solvent extraction chamber heats the shale as it moves through the chamber and thus enables the shale to go into the retort at a temperature equal to the boiling point of the solvent. Another feature provided by the use of very hot oil on the shale is the advantage derived by the increased ease and rapidity with which the oil soaked shale is treated in a retort to destructive distillation. The process has been found to operate much more readily than was the case where relatively dry shale was subjected to distillation and this is probably due to the fact

that dry shale is an extremely poor conductor of heat and consequently distillation of shale must be not only slow but wasteful because of the time and fuel used for completing the distillation. Contrasted to the treatment of dry shale, the present process, by treating oil soaked shale, and particularly shale soaked with hot oil, shortens the required period of heating because of the initial rise in temperature due to the presence of hot oil extending into the center of each particle of shale and the fact that oil soaked shale is a better conductor of heat than the same shale in a drier condition.

The particular apparatus in which the process is conducted includes a retort for the distillation of the shale which has been previously oil soaked, a treatment chamber for subjecting untreated shale to a bath of hot liquid oil, and the necessary communicating pipes providing for the passage of the products of distillation from the retort to a point where these products may be conveniently condensed to a sufficient degree to provide the materials used as the liquid bath in the treatment chamber. Details providing for the efficient and continuous operation of the apparatus and process include the use of a screw, chain type, or any other suitable type of conveyor retort positioned substantially horizontally in a furnace, an inclined tubular treatment chamber above the retort tube and outside the furnace, and the relative position of the openings for the introduction and removal of shale, the relative position of the pipes for the removal of liquid oil and aeriform material from the treatment chamber, the relative length of the pipes connected to the treatment chamber, and the mounting of a conveyor within the treatment chamber for the removal of shale.

The above and additional details and advantages of the apparatus and process are described and claimed in the following specification and claims, and illustrated in the accompanying drawings, in which:

Figure 1 is a side elevation, partly broken away, of apparatus including a retort and treatment chamber involving the features of the invention;

Figure 2 is an enlarged view, partly broken away and in partial section, illustrating the relation between the retort having the screw conveyors, and the inclined treatment chamber positioned above the retort; and

Figure 3 is a diagrammatic view illustrating the relative direction of rotation of the conveyor shafts, looking in the direction of the arrows on the line 3—3 of Figure 2.

5 Like numerals refer to like parts in the different figures of the drawing.

Referring in detail to the drawings of the apparatus which has been successfully used in conducting the process of the invention,

- 10 1 represents the masonry construction of the furnace, either concrete, stone or brick, but preferably fire-brick, such as will stand severe temperatures. A suitable stack 2 is provided for leading off the furnace fumes,
- 15 smoke, and gases of combustion. A source of heat is provided by burners 3^a located at the lower part of the furnace and fed by suitable pipes 3 providing liquid or gaseous fuel obtained during the operation of the
- 20 process and apparatus, as will be hereinafter further explained. The furnace may be braced by suitable buck stays, not shown, which enclose the outer walls of the furnace and hold the same to a suitable masonry or
- 25 concrete base. The flame and hot gases from the burner nozzles is projected inwardly and passed upwardly in the furnace over a horizontally extending partition 4 and upward to ultimately escape through the stack 2.
- 30 During the upward movement the heat comes into direct contact with the exterior of a plurality of longitudinally positioned retort tubes, as will be described.

The drawing illustrates three cracking tubes or retort tubes 5, 6 and 7, positioned one above the other and substantially horizontally. Within the tubes 5, 6 and 7 are respective screw conveyors 5^a, 6^a and 7^a, mounted on and adapted to turn with shafts 5^b, 6^b and 7^b, respectively. Suitable journal boxes or stuffing boxes are indicated for the respective shafts at 5^c, 6^c and 7^c. Materials within the tube 5 are passed to the left, referring to Figure 2, and are dropped through 45 the communicating pipe 8 into the end of the tube 6, and similarly these materials are passed in the opposite direction in the tube 6 and are permitted to drop through the communicating pipe 9 to the lowermost tube 7, in which latter the materials are again moved to the left and are finally dropped into the discharge pipe 10 for spent shale. Discharge pipe 10 has a rotary valve 10^a adapted to periodically move to discharge 55 shale in measured quantities, but not to permit the passage of air or gases into or out of the retort. The valve 10^a is mounted on a shaft 10^b and operated by the same power means as the shafts of the retort conveyors, 60 as will be described. The direction of travel of the contents of the apparatus is indicated by arrows.

Immediately above the retort and furnace is mounted a treatment chamber 11 adapted 65 to contain a pool or bath of liquid oil. This

chamber is illustrated as an inclined tubular longitudinally extending member having its lower end adjacent the outlet end of the retort and its upper end positioned above the inlet end of the upper retort tube 5. A 70 pipe 12 is indicated on the upper side of and leading from an opening in the chamber 11 adjacent the lower end thereof and communicates with a reservoir 13 above the same, which reservoir is provided with a suitable 75 funnel shaped opening 14. At the opposite and upper end of the chamber 11 and on the underneath side thereof is a discharge opening having a pipe 15 leading therefrom and extending downwardly as a supply pipe for 80 the receiving end of the retort tube 5. A screw conveyor 11^a is mounted within the chamber 11 and positioned substantially on the bottom thereof so as to move shale and solid material along the inclined floor of the 85 chamber from the lower end thereof and dump such material into the pipe 15. The screw conveyor 11^a is mounted on shaft 11^b which in turn is provided with the necessary stuffing boxes or journal boxes 11^c at the 90 ends of the chamber 11. The invention provides that the conveyor 11^a should move in such a manner as to carry relatively small amounts comparatively slowly from the lower end of the chamber 11 to the discharge 95 opening at the pipe 15. The invention also provides that the lower end of the chamber 11 constantly contain a bath or pool of liquid oil which normally covers the lower end of the pipe 12 and rises within that pipe and 100 into the hopper 13 whenever the pressure may so require this movement. Likewise it is necessary that the upper end of the pipe 15, namely the discharge end of the chamber, be above the fluid level within the chamber so that the screw conveyor 11^a may move shale material out of the liquid oil bath before dumping the shale material into the pipe 15. On the upper side of the chamber 105 is a discharge opening having a pipe 16 for the removal of gases and vapors from a region above the pool of oil. Another discharge opening having a pipe 17 is provided at a lower point on the chamber 11 for the removal of liquid oil provided and formed 110 during the operation of the process and apparatus. This pipe 17 is attached to the chamber 11 at a point well removed from the lower side of the chamber so that no solid material or shale will be drawn off with the oil, and in the preferred arrangement this pipe is in close proximity to the pipe 12 near the upper surface but toward the lower end of the chamber 11. An upwardly extending pipe 17^a having its upper end open 115 to the air is connected to the pipe 17 to permit equalization of pressure and to prevent siphoning of oil through the pipe 17 when flow is started through this pipe. The pipe 17^a should extend approximately as high as 120

the upper end of the reservoir 13 so that the oil also may rise within this pipe subject to pressures within the chamber 11, as will be described.

5 The pipe 16 for the removal of aeriform materials preferably extends upward as an elongated run-back pipe, and is connected with a stone tower 18, and from this tower gases and lighter vapors are removed 10 through the pipe 19 and passed through the coils of a condenser 20 positioned in the condenser tank 21. Liquid oil formed within the stone tower is drawn off through the pipe 22 and emptied into a distillate tank 15 23. Materials condensed in the coils 20 are removed through a pipe 20^a and deposited in a gasoline tank 24. Gases remaining after passage through the condenser are led upward away from the pipe 20^a and into 20 a gas scrubber 25 by means of a pipe 20^b connected to the lower end of the scrubber. The gases issuing from the scrubber at the top thereof are led through the pipe 3 to the burner nozzle 3^a in the furnace. The 25 pipe 17 for the removal of liquid oil from the oil bath in the chamber 11, extends the length of the apparatus, back of the condenser in Figure 1, and is connected to the pipe 22 which conducts liquid oil into the 30 distillate tank 23.

Driving means for turning the shafts 5^b, 6^b, 7^b and 11^b is provided by the main drive shaft 26 mounted in suitable bearings, not shown, and driven from any suitable source 35 of power. Referring to Figures 2 and 3, it will be noted that the shaft 26 moves clockwise and turns a sprocket gear 27, which in turn operates a continuous chain 28, which latter in turn extends over the 40 sprocket gears 5^d, 6^d and 7^d which are mounted respectively on the conveyor shafts 5^b, 6^b and 7^b. The shaft 5^b is provided with a second sprocket gear 5^e, which is adapted to drive a chain 5^f passing over a sprocket 45 gear 11^d mounted on the conveyor shaft 11^b. A universal joint in the shaft 11^b is indicated at 11^e to take care of the angle due to the inclination of the tank 11. At the lower side of the apparatus the conveyor 50 shaft 7^b is provided with a second sprocket wheel 7^e which drives a chain 7^f passing over a sprocket wheel 10^c mounted on the valve shaft 10^b, thus constituting operating 55 means for the valve 10^a. The arrows in Figure 3 indicate the relative direction of rotation of the conveyor shafts and sprocket wheels.

At the upper end of the treatment chamber 11 is a pipe 11^f for the introduction 60 of materials used for washing out the treatment chamber, and at the lower end is a corresponding drain pipe 11^g for removing such materials.

65 The process and apparatus has been satisfactorily operated with apparatus in

which the retort tubes 5, 6 and 7 were approximately of six inch bore, and in which a conveyor screw of five and three-quarter inches was operated. The invention preferably uses a tubular treatment chamber 11 70 which has a bore of from twenty-four to thirty inches in which the conveyor member is approximately eight inches. The operation of the process is not necessarily dependent on the relative size of the chamber and conveyor therein, but under certain conditions may be operated satisfactorily with a conveyor substantially filling the chamber, or by any kind of conveyor capable of moving shale and solid material 75 from the pool of oil, out of the same and into the receiving end of the retort.

In the normal operation of the process, when first starting the same, liquid oil is 80 poured into the opening 14 and sufficient is introduced to cover the lower end of the pipe 12, thus forming a liquid seal for this pipe. Such oil is preferably a distillate obtained from previous distillation, or what is known as tops or distillate, but any other 85 liquid oil from petroleum is sufficiently effective as a seal to serve for the purpose. The use of water as a seal for the initial operation has been satisfactorily applied.

Crushed shale containing the oil to be 90 extracted in reduced form and containing chiefly lumps capable of passing through a two inch screen is added by dumping the same in small amounts into the opening 14. The shale is introduced thus into the oil bath and is subjected thereby to a combined solvent treatment and oil soaking treatment. The conveyors are set in motion and the retort heated. It is the practice to introduce 95 shale into the reservoir 13 as fast as it is removed by the screw conveyor 11^a, thus giving a mechanical advantage of preventing an accumulation of the shale, which because part of it is finely divided when stirred 100 up with the oil, becomes a mud which is objectionable when passed into pipes. The column of shale moved along the floor of the chamber 11 is relatively small compared to the capacity of the chamber, usually not 105 more than 10 per cent as much shale being present as compared to the volume of the oil bath, and frequently the amount of shale is in much lower proportion. This continuous movement of the shale in small quantities is such that the shale is constantly in 110 agitation and being stirred and is in constant contact with new portions of a relatively large bath of solvent oil. As the shale is moved from the chamber and through the retorts in the retort furnace it 115 is subjected to increased temperatures during its progress through the apparatus. This heat treatment in the retorts drives off 120 all oil material present in the shale and adhering thereto, and all that has not been re-

130

moved by the solvent action of the bath of oil in the chamber 11. The gases and vapors generated within the retort tubes 5, 6 and 7 are passed upward through the pipe 15 and into the treatment chamber 11. In this region they come into contact with the relatively cooler walls of the chamber, the bath of oil with the fresh shale therein, and a substantial portion of the material is condensed and flows to the lower end of the chamber to supplement the volume of liquid oil. The nature and the amount of the materials so condensed depends on the temperature in the retort, in part, but chiefly on the relative size and coolness of the walls of the treatment chamber 11 and the length of the run-back pipe 16. The chamber 11 may be covered with insulating material to maintain heat conditions constant, or it may be artificially cooled. Likewise, the length of the pipe 16 may be varied and it also may be insulated or artificially cooled, such changes depending on the relative nature of the condensed materials to be used as the solvent bath.

The blast of flame from the burners 3^a provides a temperature in the lower retort hotter than the temperature in the upper retort. The temperature around the retort tubes should be from 900° F. to 1400° F. depending on the arrangement of flues and the disposition of the retort tubes within the furnace 1. The temperature within the retort tubes should be at least 550° F., and for the practical rapid operation about 700° F. is desired. However, the temperature within the tube does not have to be as high as ordinarily used for destructive distillation in small retorts, because in the present invention the heat is transmitted with comparative rapidity from the outside to the inside of each piece of shale; this being due, as hereinbefore explained, to the preliminary heating by the addition of the hot solvent oil which thoroughly soaks each piece of shale and likewise raises the temperature of the same. The product is improved because of the cracking which takes place within the lumps of shale, this particular cracking being improved by the presence of the shale itself. The temperature within the extraction chamber 11 is substantially the same as the temperature of the vapors issuing from the retort tubes through the pipe 15, as they are condensed to form the liquid of the extracting bath. These vapors thus condensed are approximately at a temperature of 300° F., and sometimes above, and sometimes below, depending on the position of the chamber 11 relative to the outside air, the distance from the furnace, and the constant cooling effected by such conditions.

The process is capable of operation at ordinary atmospheric pressure, under partial

vacuum, and also under increased pressure. In the ordinary operation, the liquid oil in the lower end of the chamber 11, by covering the lower end of the pipe 12, merely provides a liquid seal and empties out through the pipe 17, flowing to the distillate tank 23, and no pressure different from atmospheric pressure is used. A gain in efficiency has been obtained when pressures up to 70 pounds at least have been applied, and under increased pressure extraction takes place more rapidly and completely on account of the higher temperature at which the solvent remains liquid instead of vaporizing. Pressures may be built up by partially closing the valves in the pipes 16 and 17, and the operation of an accumulation of pressure causes the liquid within the chamber 11 to back up through the pipe 12 and into the hopper or reservoir 13 until the hydrostatic pressure of this column of liquid is sufficient to balance the pressure within the apparatus. When the oil is thus backed up in the pipe 12 and the reservoir 13, it also rises in the air vent pipe 17^a, which latter should be high enough to permit this rise in liquid level.

The liquid oil taken off through the pipe 17 from the liquid extraction bath in the lower end of chamber 11 differs from the liquid obtained from the vapors which pass off through the pipe 16, because the former contains more or less of dissolved material extracted from the shale. The liquid in the chamber 11 also contains a more readily condensed vapor passed from the retort, and therefore has a higher specific gravity and higher boiling point than the vapors and the liquids condensed therefrom which are driven off through the pipe 16.

The process and apparatus has been successfully worked in the treatment of Monterey shale mined in California. Also, it has been successfully used in treating shales mined near Elko, Nevada, which latter contain large amounts of oil and wax which can be extracted by solvents. The invention has also been successfully used with shale taken from the Uintah Basin of Colorado and Utah, and also has successfully been used with oil soaked sand.

The process and apparatus has produced remarkable results by using the steps of operation and the details hereinbefore specified. These features include the use of materials extracted by distillation as the material of a solvent bath for treating shale. Other arrangements capable of performing the steps specified for the process may be possible, but such arrangements are considered as within the scope of the process of this invention. For instance, the treatment chamber could extend downward from the right of the furnace so as to lower the chamber and in this case the upper end of the treatment chamber would have the same rel-

ative position as regards the connecting pipe 15, but the lower end of the chamber would be nearer the ground and consequently the reservoir 13 would be more readily reached. 5 This arrangement might serve also to extend the lower end of the treatment chamber toward the source of shale supply thereby reducing the amount of conveyor apparatus necessary. The apparatus arrangement 10 illustrated with the treatment chamber above the retort serves to economize floor space although the upper end of the reservoir 13 may not be as easily reached as if the treatment chamber was inclined downwardly toward the ground and positioned at one side of the furnace.

The term hydrocarbon oil material is understood to include all material removable from the shale by the process described and 20 claimed. It is known that certain shale, such as the shale at Casmalia, California, contains considerable amounts of resin, which resin is removed from the shale by the process of this invention, along with the oil 25 technically known as petroleum oil. The oil and resin may be separated by known refining steps. It is also known to me that the oil found near beds of shale, which beds contain such resin, also contains in solution, 30 amounts of resin and allied oxidized bodies such as tar and wax, and that this material may be recovered and separated by treating the oil as it is obtained from the ground. The presence of such materials in solution in 35 oil in nature indicates the correctness of the theory of the present invention, which provides for the solvent extraction of the shale by the solvent obtained from the shale.

What I claim is:

40 1. Apparatus for extracting hydrocarbon oil material from oil bearing shales which apparatus comprises retort means for distilling shale, a treatment chamber capable of holding a bath of oil and having an opening for the introduction of fresh shale, a shale discharge opening for the discharge of treated shale, a discharge opening for the aeriform material produced, and an opening for the discharge of extracted oil 45 material, means for removing shale from said chamber and passing it to said shale discharge opening, and a pipe directly connecting said chamber and said retort for conducting directly into said chamber material distilled from shale in said retort and in aeriform condition.

50 2. Apparatus for extracting hydrocarbon oil material from oil bearing shales which apparatus comprises retort means for distilling shale, a treatment chamber capable of holding a bath of oil and having an opening for the introduction of fresh shale, a shale discharge opening for the discharge of treated shale to the said retort, a discharge opening for the aeriform material produced, and an opening for the discharge 55

of extracted oil material, means for removing shale from said chamber and passing it to said shale discharge opening, and a pipe directly connecting said chamber and said retort for conducting directly into said chamber material distilled from shale in said retort and in aeriform condition. 70

3. Apparatus for extracting hydrocarbon oil material from oil bearing shales which apparatus comprises retort means for distilling shale, a treatment chamber having its outer surface in contact with the atmosphere and capable of holding a bath of oil and having an opening for the introduction of fresh shale, a shale discharge opening for the discharge of treated shale to the said retort, a discharge opening for the aeriform material produced, and an opening for the discharge of extracted oil material, means for removing shale from said chamber and 80 passing it to said shale discharge opening, and a pipe directly connecting said chamber and said retort for conducting directly into said chamber material distilled from shale in said retort. 85

4. Apparatus for extracting hydrocarbon oil material from oil bearing shales which apparatus comprises retort means for distilling shale, a treatment chamber capable of holding a bath of oil and having an opening for the introduction of fresh shale, a shale discharge opening for the discharge of treated shale to the said retort positioned directly above a receiving opening in said retort, a discharge opening for the aeriform material produced, and an opening for the discharge of extracted oil material, means for removing shale from said chamber and passing it to said shale discharge opening, and a pipe directly connecting said chamber and said retort for conducting directly into said chamber material distilled from shale in said retort and in aeriform condition. 90 95

5. Apparatus for extracting hydrocarbon oil material from oil bearing shale which apparatus comprises a furnace, a treatment chamber on the outside of said furnace capable of holding a bath of oil and having an opening for the introduction of fresh shale, an opening for the discharge of treated shale, an opening for the discharge of aeriform material, and an opening for the discharge of extracted oil material located higher than said opening for the introduction of fresh shale, means for removing shale from said chamber, retort means within said furnace for distilling shale, and communicating means for directly conducting into said treatment chamber material distilled from shale in said retort. 110 115 120

6. Apparatus for extracting hydrocarbon oil material from oil bearing shale which apparatus comprises a treatment chamber capable of holding a bath of oil and having an opening for the introduction of fresh 125 130

shale, an opening for the discharge of treated shale, an opening for the discharge of aeriform material, and an opening for the discharge of extracted oil material, 5 means for removing shale from said chamber, retort means for distilling shale, and communicating means for conducting into said treatment chamber material extracted from shale in said retort and in aeriform 10 condition, said chamber having a condensing surface in the interior thereof for condensing and returning to said bath aeriform material so introduced into said chamber.

7. Apparatus for extracting hydrocarbon oil material from oil bearing shale which apparatus comprises a treatment chamber capable of holding a bath of oil and having an opening for the introduction of fresh shale, an opening for the discharge of 15 treated shale, an opening for the discharge of aeriform material, and an opening for the discharge of extracted oil material, conveyor means within said chamber and co-operating with the lower inner surface thereof 20 for removing shale and solid material from said chamber, retort means for distilling such shale and solid material, and communicating means for conducting directly 25 into said treatment chamber material distilled from shale in said retort.

8. Apparatus for extracting hydrocarbon oil material from oil bearing shale which apparatus comprises a treatment chamber capable of holding a bath of oil and having 30 an opening for the introduction of fresh shale, an opening for the discharge of treated shale, and an opening for the discharge of extracted oil material, screw conveyor means extending along the floor of 35 said chamber for removing shale and solid material from said chamber, retort means for distilling shale, and communicating means for conducting directly into said treatment chamber material distilled from 40 shale in said retort.

9. Apparatus for extracting hydrocarbon oil material from oil bearing shale which apparatus comprises a treatment chamber capable of holding a bath of oil and having 45 an opening for the introduction of fresh shale, an opening for the discharge of treated shale, and an opening for the discharge of extracted oil material, screw conveyor means adjacent the floor of said chamber and extending at least from a point adjacent 50 the opening for the introduction of shale to said opening for the discharge of treated shale for removing shale from said chamber, retort means for distilling shale, and communicating means for conducting directly 55 into said treatment chamber material distilled from shale in said retort.

10. Apparatus for extracting hydrocarbon oil material from oil bearing shale 60 which apparatus comprises a treatment

chamber capable of holding a bath of oil and having an opening adjacent one end thereof and spaced from the bottom for the introduction of fresh shale, an opening for the discharge of treated shale located at the 70 opposite end of said chamber and substantially at the floor thereof, and an opening for the discharge of extracted oil material, screw conveyor means adjacent the floor of said chamber and extending at least 75 from a point adjacent the opening for the introduction of shale to said opening for the discharge of treated shale for removing shale from said chamber, a screw conveyor 80 retort for distilling shale in communication with said chamber, and a connecting pipe extending directly between said retort and said opening in said chamber for the discharge of shale, said connecting pipe constituting means for conducting volatile products from 85 said retort directly into said treatment chamber.

11. Apparatus for extracting hydrocarbon oil material from oil bearing shale which apparatus comprises a retort, a treatment chamber capable of holding a bath of oil positioned above said retort, said chamber having an opening for the introduction of fresh shale, an opening for the discharge of extracted material, a discharge passageway for treated shale extending from a point in said chamber relatively higher than said opening for the discharge of extracted material, downwardly to said retort, said passageway constituting means for conducting volatile products from said retort directly into said treatment chamber.

12. Apparatus for extracting hydrocarbon oil material from oil bearing shale which apparatus comprises a screw conveyor retort, a treatment chamber capable of holding a bath of oil positioned above said retort and having the floor thereof tilted, said chamber having an opening in the upper side thereof for the introduction of shale, a communicating passageway between said chamber and said retort extending from an opening in the upper end of said tilted chamber floor downwardly into the top of said retort, and conveyor means 110 within said chamber for moving shale and solid material from the lower side of said tilted floor and discharging the same into said passageway and into said retort, said passageway constituting means for conducting volatile products from said retort directly into said treatment chamber.

13. Apparatus for extracting hydrocarbon oil material from oil bearing shale which apparatus comprises a horizontally positioned screw conveyor retort, an inclined tubular treatment chamber positioned above said retort and capable of holding a bath of oil in the lower end thereof, an upwardly extending supply pipe mounted on the up- 125

per side of said chamber adjacent the lower end thereof, a communicating pipe extending from the floor of said chamber adjacent the upper end thereof and communicating with one end of said retort, and screw conveyor means within said chamber extending substantially the length thereof and adjacent the floor thereof but spaced from the roof thereof for moving shale from the lower end 10 of said chamber to said communicating pipe, the uppermost end of said communicating pipe at the floor of said chamber being higher than the lower end of the said supply pipe, said communicating pipe constituting means for conducting volatile products from said retort directly into said treatment chamber.

14. Apparatus for extracting hydrocarbon oil material from oil bearing shale which apparatus comprises a horizontally positioned screw conveyor retort, a furnace enclosing said retort, an inclined tubular treatment chamber positioned above said furnace and said retort and capable of holding a bath of oil in the lower end thereof, an upwardly extending supply pipe mounted on the upper side of said chamber adjacent the lower end thereof, a communicating pipe extending from the floor of said chamber adjacent the upper end thereof and communicating with one end of said retort, and screw conveyor means within said chamber extending substantially the length thereof and adjacent the floor thereof for moving shale from the lower end of said chamber to said communicating pipe, the uppermost end of said communicating pipe at the floor of said chamber being higher than the lower end of said supply pipe, said communicating pipe constituting means for conducting volatile products from said retort directly into said treatment chamber.

15. Apparatus for extracting hydrocarbon oil material from oil bearing shale which apparatus comprises a horizontally positioned screw conveyor retort, an inclined tubular treatment chamber positioned above said retort and capable of holding a bath of oil in the lower end thereof, an upwardly extending supply pipe mounted on the upper side of said chamber adjacent the lower end thereof, a communicating pipe extending from the floor of said chamber adjacent the upper end thereof and communicating with one end of said retort, a pipe extending from said chamber for the removal of aeriform material, and screw conveyor means within said chamber extending substantially the length thereof and adjacent the floor thereof for moving shale from the lower end of said chamber to said communicating pipe, the uppermost end of said communicating pipe at the floor of said chamber being higher than the lower end of the said supply pipe, said communicating pipe constituting means for conducting volatile products from said retort directly into said treatment chamber.

ducts from said retort directly into said treatment chamber.

16. Apparatus for extracting hydrocarbon oil material from oil bearing shale which apparatus comprises a horizontally positioned screw conveyor retort, an inclined tubular treatment chamber positioned above said retort and capable of holding a bath of oil in the lower end thereof, an upwardly extending supply pipe mounted on the upper side of said chamber adjacent the lower end thereof, a communicating pipe extending from the floor of said chamber adjacent the upper end thereof and communicating with one end of said retort, a pipe for the removal of liquid oil connected with said chamber, and screw conveyor means within said chamber extending substantially the length thereof and adjacent the floor thereof for moving shale from the lower end of said chamber to said communicating pipe, the uppermost end of said communicating pipe at the floor of said chamber being higher than the lower end of said supply pipe, said communicating pipe constituting means for conducting volatile products from said retort directly into said treatment chamber.

17. Apparatus for extracting hydrocarbon oil material from oil bearing shale which apparatus comprises a horizontally positioned screw conveyor retort, an inclined tubular treatment chamber positioned above said retort and capable of holding a bath of oil in the lower end thereof, an upwardly extending supply pipe mounted on the upper side of said chamber adjacent the lower end thereof, a communicating pipe extending from the floor of said chamber adjacent the upper end thereof and communicating with one end of said retort, a pipe extending from said chamber for the removal of aeriform material and projecting upwardly and constituting a run-back pipe, a pipe for the removal of liquid oil connected with said chamber, and screw conveyor means within said chamber extending substantially the length thereof and adjacent the floor thereof for moving shale from the lower end of said chamber to said communicating pipe, the uppermost end of said communicating pipe at the floor of said chamber being higher than the lower end of said supply pipe, said communicating pipe constituting means for conducting volatile products from said retort directly into said treatment chamber.

In testimony whereof I affix my signature.

DAVID T. DAY.
